UNITED STATES PATENT OFFICE.

WILLIAM F. JONES AND WOODUS KELLUM, OF WILMINGTON, NORTH CAROLINA.

DESIGN FOR AN ADVERTISING-CABINET.

52,167.

Specification for Design.

Patented July 9, 1918.

Application filed March 13, 1918. Serial No. 222,250. Term of patent 14 years.

To all whom it may concern:

Be it known that we, WILLIAM F. JONES and WOODUS KELLUM, citizens of the United States, residing at Wilmington, in the county of New Hanover and State of North Carolina, have invented a new, original, and ornamental Design for Advertising-Cabinets, of which the following is a specification, reference being had to the accompanying drawing, forming part thereof.

Fig. 2 is a view in front elevation of the advertising cabinet.

We claim:

The ornamental design for an advertising cabinet, substantially as shown.

WILLIAM F. JONES.
WOODUS KELLUM.

Witnesses:

JOHN J. FURLONG,
G. W. BORNEMANN.
